CLAIM

The ornamental design for a lid for a trash receptacle, as shown and described.

DESCRIPTION

FIG. 1 is a top, front perspective view of the claimed design for a lid for a trash receptacle;

FIG. 2 is a front view thereof;

FIG. 3 is a back view thereof;

FIG. 4 is a left view thereof;

FIG. 5 is a right view thereof; and,

FIG. 6 is a top view thereof.

The broken lines in the drawings depict portions of the lid for a trash receptacle that form no part of the claimed design.
